STORE FRONT CONSTRUCTION

Francis J. Plym, Niles, Mich., assignor to The
Kawneer Company, Niles, Mich., a corporation
of Michigan

Application June 22, 1935, Serial No. 27,886

2 Claims. (Cl. 189—78)

The present invention relates to store front constructions and more particularly to a novel sash member for mounting adjoining panes of glass.

Among the objects of the present invention is to provide a novel construction of sash bar for mounting adjacent or adjoining panes of glass.

A further object is to provide a novel sash retaining bar having means for adjustably mounting the panes of glass from the interior.

Another object of the present invention is the provision of a novel division, corner or reverse bar for joining adjacent panes of glass, in which the face or outer part or moulding is rigid or fixed and the adjustment of the glass is from the interior. This feature of the invention permits a perfect mitre or joint where the sections of the store front construction are united.

A further object of the invention is the provision of a sash construction of the type disclosed, consisting of a minimum number of parts which may be standardized, and the construction assembled or mounted in a minimum amount of time without the use of experienced help.

A still further object is the provision of a novel sash construction in which the glass is retained with an equal and uniform pressure throughout its length. No screws, cam members or the like are employed, which would produce a holding pressure at spaced points only and not a uniform and continuous gripping or holding pressure as in the present device.

Another object of the present invention is the provision of a sash bar for holding panes of glass positioned at an angle to one another, which bar may be quickly and conveniently bent or formed to retain such panes regardless of the angle which they may assume. Due to the simplicity of the construction, this may be accomplished at the installation.

Yet another object of the invention is the provision of a standardized sash bar adapted to receive and retain adjacent sections of glass even though they may vary in thickness. The resilient adjusting means or strip automatically adjusts itself to the thickness of the glass.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawings, and while

I have shown therein a preferred embodiment, it is to be understood that the same is susceptible of modification and change, and comprehends other details, arrangements of parts, features and constructions without departing from the spirit of the invention.

In the drawings:

Figure 1 is a view in elevation of a store front construction.

Fig. 2 is a view in vertical cross section taken in a plane represented by the line 2—2 of Fig. 1.

Figs. 3, 4, and 5 are views in vertical cross section taken in planes represented by the lines 3—3, 4—4, and 5—5, respectively, of Fig. 1.

Fig. 6 is a fragmentary view in perspective of the novel glass holding or adjusting means.

Fig. 7 is a fragmentary view in perspective of the novel division bar of Fig. 3.

Fig. 8 is a fragmentary view in perspective of the novel corner bar of Fig. 4.

Fig. 9 is a fragmentary view in perspective of the novel reverse bar of Fig. 5.

Figs. 10 and 11 are views in vertical cross section of alternate forms of division bars.

Figs. 12 and 13 are views in vertical cross section of alternate forms of corner bars.

Fig. 14 is a view in vertical cross section of an alternate form of reverse bar.

Referring to the disclosure in Figs. 1 to 9, inclusive, of the drawings, the store front therein shown comprises a plurality of adjoining panes of glass 1, two adjacent sections or panes having their vertical edges secured or mounted in a division bar 2, other adjacent sections or panes by a corner bar 3, and still others by a reverse bar 4.

The division bar construction 2 comprises a sheet of metal having its ends bent or formed to provide oppositely extending ribs or flanges 5 and 6, and doubled-over portions forming outwardly projecting ribs or flanges 7 and 8, the ribs or flanges 5 and 7, and 6 and 8, forming a groove or channel therebetween for the reception of the edge of adjacent panes of glass. The webs or sides 9 and 10 forming the base of the opposite channels are preferably spaced apart and the metal of the bar is preferably yieldable or flexible. A face plate 11 having its opposite ends 12 and 13 bent to provide inwardly opening channels receives the flanges 5 and 6 when the flanges spring apart due to the resiliency of the material, after having been compressed. The face plate is preferably of a non-corrosive metal or other material which will withstand the elements,

while the division bar may be of any metal suitable for the purpose.

In order to retain the panes of glass in position, the invention comprehends the provision of 5 U-shaped resilient members 16 which are pressed or forced into the grooves adjacent each pane of glass and between the panes and ribs or flanges 7 and 8, and force these panes into contacting engagement with the ends 12 and 13 of the face 10 plates and/or flanges 5 and 6 of the division bar.

The corner bar construction 3 is more particularly disclosed in Figs. 4 and 8, the structure being very similar to the division bar with the exception that the flanges 17 and 18, and 19 and 15 20, extend at an angle of less than 180° from each other. The cap or face plate 21 is adapted to receive the ends of the flanges 17 and 18 within the grooves or channels 22 and 23 formed by return bend of the ends of the plate or cap.

20 The reverse bar 4 is more particularly disclosed in Figs. 5 and 9, the purpose of which is to connect adjacent panes positioned at a reverse angle to that of the corner bar 3. The construction is quite similar to a corner bar, the glass being positioned in the channels formed intermediate the flanges 24 and 25, and 26 and 27.

25 In Figs. 10 and 11 are disclosed alternate construction of division bars. In Fig. 10 the bar 28 is shown as formed in one piece of extruded 30 metal, with the oppositely projecting flanges 29 and 31, and 32 and 33, formed integral with the web 34. No separate cap or face plate is necessary.

35 In Fig. 11, the division bar 35 comprises a member provided with a central web 36 of double thickness and the ends forming oppositely projecting flanges 37 and 38. The inner part of the web is enlarged as at 39, and is received in a groove or channel in an inner sash member 40 having oppositely projecting flanges 41 and 42. A cap or face plate 44 is adapted to cover the flanges 37 and 38.

40 In Fig. 12 there is disclosed a corner bar 43 formed of extruded metal in which the projecting 45 flanges 44 and 45, and 46 and 47, are formed integral with the web 48.

45 Fig. 13 discloses a further alternate construction of corner bar 49, in which the sash member is formed of two parts but interconnected. In 50 this form, the web 50 is of double thickness with the ends thereof forming flanges or ribs 51 and 52. The inner part of the web is provided with an enlargement 53 adapted to seat in a groove or channel in the inner sash member 54. A cap or 55 face plate 55 of any suitable contour may be provided.

50 Fig. 14 discloses an alternate construction of reverse bar 56 in which the elements are generally similar to those shown in the corner bar of Fig. 60 13, but modified to retain glass set at a reverse

angle. In this construction, the web 57 is provided with projecting flanges 58 and 59, the inner end of the web being formed with an enlargement 60 adapted to be received in a channel in the inner sash member 61 having projecting flanges 62 5 and 63 for the reception of the resilient securing strips 16. A face plate 64 is also provided, if desired.

10 In each of the forms disclosed, the inner flange, rib or projection is of curved or arcuate formation 15 so that a side of the resilient member seats against and takes the contour of this flange or rib and becomes locked or anchored in position.

15 It will be readily apparent that the invention comprises a minimum number of parts which can be readily assembled and which retain adjacent panes of glass in their adjusted position. By the present construction, the flanges may be readily bent or formed to accommodate glass set at any desired angle. This may be done at the installation, and thus the present construction lends itself to standardization.

20 The entire adjustment is accomplished from the rear of the glass with the outer sash members always in perfect alignment and maintained so. 25 In order to more securely retain the resilient adjusting strips or members, the flanges or ribs of the inner sash member are preferably curved.

25 It is to be understood that suitable drain and 30 ventilating openings are provided.

Having thus described the invention, I claim:

1. A bar construction for joining adjacent sections or panes of glass, comprising a member formed with outwardly projecting and longitudinally extending flanges providing a channel on the opposite sides of said bar for receiving said adjacent sections or panes, the inner flanges being curved, and a continuous strip of resilient metal adapted to be forced into each channel intermediate the inner face of each section or pane and the inner flange with a side of said strip taking the contour of the inner flange and thereby being anchored in position and the other side seating against the pane.

2. A sash construction for joining the edges of 45 adjoining panes of glass mounted at an angle to one another, comprising a bar having formed integral therewith outwardly projecting flanges adapted to provide oppositely opening recesses, each recess adapted to receive an edge of one of 50 the panes with the flanges which form the sides of the recess spaced apart a distance greater than the thickness of the glass and one of said flanges being curved, and a resilient U-shaped member 55 adapted to be inserted intermediate the rear face of the panes and the rear side of the recess with said member seating against the interior of said curved flange and thereby anchored in position.
